Inventor:
Reese Evans.

REESE EVANS, OF MILLTOWN, NEW JERSEY.

Letters Patent No. 88,860, dated April 13, 1869.

IMPROVED FELT-SHOE.

The Schedule referred to in these Letters Patent and making part of the same.

To all whom it may concern:

Be it known that I, REESE EVANS, of Milltown, in the county of Middlesex, in the State of New Jersey, have invented a new and improved Mode of Fastening Together the Vamp and Quarter of Shoes composed of Felt and Rubber; and I do hereby declare that the following is a full and exact description thereof, reference being had to the accompanying drawings, and to the letters of reference marked thereon, in which—

Figure 1 is a view of the upper portions of a felt and rubber shoe, the quarter being turned down so as to show my mode of connecting it to the vamp.

Figure 2 is a similar view of the opposite side.

Figure 3 is also a view of the upper part of the same kind of a shoe, representing the quarter and vamp stitched together, the usual way of connecting them.

This invention relates to an improvement in shoes made of felt and rubber.

The object of the invention is to secure the quarter to the vamp, so that it will not be so easily loosened as it would were it stitched in the usual way.

This object is attained by forming the quarter with a small piece of felt on each side, with the lower end turned up and cemented to the vamp.

To enable those skilled in the art to make and use my invention, I will proceed to describe it.

A represents the vamp of a shoe, made of felt and rubber.

B is the quarter, the inner sides of which last, or where the strap and buckle come, have strips of felt cemented thereto, as shown at C, in fig. 1 and fig. 2.

These pieces are made fast to the quarter as far down as where the stitching usually comes, when they are turned up on the vamp and cemented thereto, as represented at D, in fig. 1 and fig. 2.

The usual way of stitching the quarter to the vamp, as shown at E, in fig. 3, is liable to rip apart, while my invention cannot.

What I claim as my invention, and desire to secure by Letters Patent, is—

The mode of fastening together the quarter and vamp of shoes composed of felt and rubber, by cementing parts D, as shown in fig. 1 and fig. 2, to the vamp A, the whole being arranged as and for the purpose set forth.
